UNITED STATES PATENT OFFICE.

WILLIAM HAMILTON HANNA, OF PETERSBURG, ILLINOIS.

FEEDING DEVICE FOR SEWING-MACHINES.

SPECIFICATION forming part of Letters Patent No. 445,468, dated January 27, 1891.

Application filed April 26, 1890. Serial No. 349,602. (No model.)

To all whom it may concern:

Be it known that I, WILLIAM HAMILTON HANNA, a citizen of the United States, and a resident of Petersburg, in the county of Me- 5 nard and State of Illinois, have invented cer- tain new and useful Improvements in Sewing- Machines; and I do hereby declare the fol- lowing to be a full, clear, and exact descrip- 10 tion of the invention, such as will enable oth- ers skilled in the art to which it appertains to make and use the same.

My invention relates to improvements in feed mechanisms for sewing-machines adapt- ed for use on universal-feed machines and on 15 sewing-machines generally; and the object of the invention is to overcome stoppage of the work by a lump or knot forming in the throat, which frequently causes the foot-feed to slip on the work and the failure of the foot-feed 20 to feed the work, whereby the needle is made to pass through the same hole or perforation a number of times, thus enlarging the knot or lump, and the needle also cuts or "chaws" the work for some distance, thereby necessi- 25 tating the removal of the work from the ma- chine and the cutting out of the lumps or knots. To overcome these objections I pro- vide a fixed or permanent tubular throat, which is arranged in line or in the same ver- 30 tical plane with the needle to provide a pas- sage for the same and the thread, a vibrat- ing throat-plate arranged over the tubular throat and having an aperture or perforation in the boundary wall of which is continuous, 35 which is adapted to receive the tubular throat when said throat-plate is depressed, and mech- anism for lifting the throat-plate above the plane of the upper edge of the tubular throat at the instant that the foot-feed engages the 40 work, said throat-plate being held in its ele- vated position by the actuating mechanism provided therefor while the foot is engaged with and feeding the work.

My invention further consists in the com- 45 bination of devices and peculiar construction and arrangement of parts, as will be herein- after fully described and claimed.

To enable others to more readily understand my invention, I have illustrated the same in 50 the accompanying drawings, in which—

Figure I is an elevation of my improve-

ments, showing the arm and other parts of the machine by dotted lines. Fig. II is a vertical sectional view through the throat-plate, the tubular throat, and the actuating devices 55 for moving the throat-plate, showing the said throat-plate depressed and the parts in cor- responding position. Fig. III is a view cor- responding to Fig. II, with the throat-plate elevated and the parts in their reversed posi- 60 tions. Fig. IV is a detail perspective view of the throat-plate, showing the same in an in- verted position.

I have shown my improvement as adapted to a universal-feed sewing-machine which em- 65 ploys a rotary shuttle and top feeding mech- anism, and in the accompanying drawings 1 designates the arm or bed of the machine; 2, the rotary shuttle, arranged within the race in a circular recess in said arm; 3, the main 70 shaft; 4, the foot for pressing upon and feed- ing the work, and 5 the needle-bar, which car- ries the needle and which passes through the bifurcated or forked portion at the lower ex- tremity of the foot 4. The shuttle is operated 75 by a cam 6 on the main shaft and the lever 6', having a roller which rides in the irregular groove in said cam. The feed-foot is moved by the cam 7 on one end of said main shaft, which cam engages with suitable lifters on 80 the cylinder that carries the foot, and this foot is operated in the manner well understood by those skilled in the art to which my invention relates in order to feed the work at the proper 85 interval of time.

I shall confine myself more particularly to a description of my improvements and refer to such parts of the machine as are in com- mon use to enable others to more readily un- 90 derstand the purposes and operation of the present invention.

My improvements consist of a tubular throat 10, a vibrating throat-plate 11, and means for actuating said throat-plate.

The tubular throat 10 is arranged vertically 95 in the vertical plane of the needle-bar or in the same plane as the line of movement of the needle, and said throat is fixed or permanent on the arm of the sewing-machine or the parts adjacent thereto.

The vibrating throat-plate 11 is arranged 100 over the arm 1 and the shuttle, and its free

end takes over the protruding part of the tubular throat, said throat-plate being mounted to vibrate in a vertical plane to assist the feed mechanism in moving the work. This 5 throat-plate is pivoted at one end on a horizontal transverse pivot 12, and it has a tongue which fits between the bifurcated arms 13 of a supporting-plate 14, which is normally at rest and held in place by a pivot or set-screw 10 9', which passes vertically through the supporting-plate 14; but it is obvious that by lifting the throat-plate above the tubular throat both plates can be moved horizontally to throw the tongue-plate away from the shuttle and permit access to the same. The throat-plate is normally depressed by a spring or springs 15, preferably two in number, which springs are arranged on the lower surface or under side of the throat-plate and the supporting-plate. These springs are flat or leaf springs, and they are secured to lugs 16 on the throat-plate and also suitably secured to the supporting-plate, as shown. Near the free 20 end of this vibrating tongue-plate is formed 25 the needle-eye 17, and said vibrating throat-plate is so arranged that this eye receives the protruding part of the tubular throat when said throat-plate is depressed by the retracting springs arranged on the lower side of the 30 throat and supporting plates; but this throat-plate is positively lifted or elevated above the plane or upper end of the tubular throat at the instant that the foot-feed engages the work, and said plate is held in such elevated 35 position by the following mechanism: A cam or wedge-shaped surface 18 is provided on the lower surface of the vibrating throat-plate at a point between the needle-eye 17 in said plate and the fulcrum 12 thereof, said wedge-shaped cam being situated behind the shuttle-race or in rear of the needle where only one thread is used. With this cam 18 contacts at suitable intervals a similar cam or wedge-shaped surface 19, which is carried by 40 45 a reciprocating slide 20. This slide is fitted and arranged in suitable guides below the throat-plate, and the slide is actuated from the grooved cam 21 on the main shaft by the lever 22 and an endwise-movable rod 23, 50 which rod is bent at an intermediate point of its length and has its bent portion passing through a slot 24 in the arm 1 of the machine. The grooved cam and other operating parts of the machine are so proportioned and combined that the slide 20 is drawn in one direction to bring its wedge-shaped surface 19 in contact with the corresponding surface 18 on the throat-plate at the same instant that the foot-feed engages the fabric or work, thus 55 60 lifting the throat-plate positively and raising its free end above the tubular throat, and this throat-plate is held in its elevated position the whole time that the foot-feed is engaged in moving the work, whereby the throat-plate 65 assists the foot-feed in feeding the work the proper distance at the proper interval of time,

and all tendency toward improper and irregular feeding of the work by the foot-feed and the stoppage of the work by reason of a lump or knot of thread forming in the tubular throat 70 is obviated. As soon as the foot-feed has fed the work the slide is moved by the cam in the reverse direction, and the springs depress the throat-plate over the tubular throat at the instant that the needle-bar descends and the 75 needle and thread pass through the fabric into the throat; but when the needle-bar and needle recede and the foot-feed again engages the work the throat-plate is lifted by the slide and the operation repeated. 80

The boundary-wall of the needle-eye 17 in the throat-plate is continuous, and the upper part of said eye is countersunk or beveled, as shown.

The operation of my improvement will be 85 readily understood by those skilled in the art to which my invention relates from the foregoing description, taken in connection with the drawings.

I do not strictly confine myself to the exact 90 mechanism herein shown and described for giving the slide and its cam a rectilinear reciprocating movement to lift the vibrating throat-plate, as I am aware that other mechanical equivalents can be employed for actuating said throat-plate. 95

I am also aware that modifications in the form and proportion of parts can be made without departing from the spirit of my invention. 100

Having thus fully described my invention, what I claim as new, and desire to secure by Letters Patent, is—

1. In a sewing-machine, the combination of a tubular fixed throat, the vibrating throat-plate provided with a needle-eye at one end and hung or suspended so that its eye receives said tubular throat, the retracting-spring connected to the throat-plate, and a reciprocating slide arranged to contact with said throat-plate at suitable intervals and provided with means for giving vertical vibration to said throat-plate, substantially as and for the purpose described. 110

2. In a sewing-machine, the combination of a vibrating throat-plate pivoted at one end, having an eye at or near its free end and a wedge-shaped cam or surface at an intermediate point of its length, a fixed tubular throat arranged to enter the eye in said throat-plate, a reciprocating slide below the throat-plate and having a cam-shaped surface adapted to contact with the corresponding surface on the throat-plate, mechanism for moving the slide at suitable intervals, and a spring connected to the throat-plate to depress said plate when released from contact with the slide, as and for the purpose described. 115 120 125

3. In a sewing-machine, the combination, with the foot-feed, of a vibrating throat-plate having an eye, a fixed tubular throat arranged to enter the eye in said throat-plate when the 130

same is depressed, mechanism, substantially as described, for lifting the throat-plate at the instant the foot-feed engages the work, said throat-plate being held in its elevated position by its actuating mechanism during the interval that the foot-feed engages and feeds the work, and the springs for retracting the throat-plate after the actuating mechan-

ism is moved to allow said throat-plate to be depressed, as and for the purpose described. ^{to}

In testimony whereof I affix my signature in presence two witnesses.

WILLIAM HAMILTON HANNA.
